CLAIM

I claim the ornamental design for an automobile tire, as shown and described.

DESCRIPTION

FIG. 1 is a front perspective view of the automobile tire;

FIG. 2 is a front view thereof;

FIG. 3 is a rear view thereof;

FIG. 4 is a top view thereof;

FIG. 5 is a bottom view thereof;

FIG. 6 is a left side view thereof;

FIG. 7 is a right side view thereof; and,

FIG. 8 is an enlarged view thereof.

The broken lines in the drawings of the automobile tire are for showing portions of the automobile tire and form no part of the claimed design.
